GEORGE F. FORD, OF HOLLYWOOD, AND WALTER PITTMAN, OF HUNTINGTON PARK, CALIFORNIA, ASSIGNORS TO FIBREBOARD PRODUCTS INC., OF SAN FRANCISCO, CALIFORNIA, A CORPORATION OF DELAWARE

PRINTING, CUTTING, AND SCORING PRESS

Application filed November 18, 1929. Serial No. 407,807.

Our invention relates to printing presses, and particularly to presses of the cylinder type in which material such as fiberboard may be printed, cut, and scored for the formation of cartons, without handling between the operations.

An object of our invention is to provide means whereby the cutting and the scoring operation may be performed on the same 10 press as the printing operation, and without intermediate handling.

Another object of our invention is to provide a press in which both the printing and the cutting and scoring operations are performed under the best conditions, the quality 15 of neither being sacrificed in order that the operation may be simultaneously performed.

Still another object of our invention is to provide a means for adapting a press of well 20 known type to a new form of use, thus obviating the necessity for the manufacture of a large number of special parts and promoting interchangeability.

The invention possesses numerous other 25 objects and features of advantage, some of which, with the foregoing, will be set forth in the following description of our invention. It is to be understood that we do not limit ourselves to this disclosure of species of our 30 invention, as we may adopt variant embodiments thereof within the scope of the claims.

The simultaneous printing and cutting and scoring of material upon a unitary cylinder press has been the subject of inventive effort 35 for at least forty years. Such presses as have thus far been placed on the market have been only partly satisfactory, owing to the different requirements of the two operations, and to the fact that the quality of the 40 work of one or both types has been unfavorably affected by the compromises of design.

For light work, cutting and scoring rules have been included in the same chase as the printing type. This is quite impractical for 45 working in fiberboard or other heavy material, since the counterdie necessary for the cutting and scoring operation is unsuitable as a support for a surface to be printed.

The expedient most used has been to cut 50 and score with a rule die secured to a recipro-

cating bed, with a counterdie carried by an impression cylinder, and to print from a type carrying roller bearing against the side of the same cylinder. Varying thickness of counterdie and of material worked on result 55 in slightly different peripheral speeds for the impression and type cylinders and consequent smearing and failure to register.

In broadly descriptive terms the press of our invention is of the type in which the 60 material operated upon is pressed against the type, and in this case also against the cutting and scoring rules, which are secured to a flat reciprocating bed. The impressions are made by continuously rotating impression 65 cylinders. The cylinders receive the material to be operated upon, hold it while the impression is being made, and transfer it from one to the other, in the same general manner as the well known two-color printing 70 press.

The first cylinder is the printing cylinder, and is substantially the same as in the ordinary two-color press. The second cylinder is the cutting cylinder, and differs from the 75 second cylinder in the two-color press in being of slightly smaller diameter than the first cylinder and in having attached thereto a removable, semi-cylindrical jacket to which a cutting and scoring counterdie is secured, 80 and beneath which a tympan is placed for insuring uniform impression.

The counterdie is built up of layers of paper which are formed and worked to provide a matrix for the cutting and forming rules 85 of the cutting and scoring die, which is locked on the press bed to reciprocate beneath the cylinder. Means are provided for stretching the jacket tightly in place upon the cylinder, and for supporting its leading edge against 90 the impact of the cutting knives. The cutting cylinder is preferably given a larger movement than the printing cylinder in order properly to clear the dies upon the recovery movement of the bed, and the register rack is 95 altered in length and position in order to damp out vibration due to the impact of the die and to prevent its transmission to the printing cylinder. A special form of delivery is also provided in order to render 100

the cylinder more accessible for removal and replacement of the jacket.

Referring to the drawings:

5 Figure 1 is the side elevation of a two cylinder, reciprocating bed press embodying our invention.

10 Figures 2 to 6 inclusive are diagrams showing the progress of the material upon the impression and transfer cylinders.

15 Figure 7 is a diagrammatic perspective view illustrating the operation of the grippers which hold the material upon the cylinder.

15 Figure 8 is a fragmentary sectional view of the cutting and scoring cylinder, showing the means of attachment of the leading edge of the jacket and the gripper mechanism.

20 Figure 9 is a view similar to Figure 8 showing the attachment of the trailing edge of the jacket.

25 Figure 10 is a plan view of a portion of the transfer cylinder.

25 Figure 11 is a cross sectional view of the transfer cylinder and portions of the impression cylinders, showing the grippers on the transfer cylinder and the openings in the cutting cylinder jacket for clearing the transfer cylinder grippers.

30 Figure 12 is a fragmentary cross sectional view of the press, showing the means for reciprocating the bed. The plane of section is on the line 12—12 of Figure 1.

35 Figure 13 is a fragmentary view, partly in cross section and partly in elevation, showing the relationship between the impression cylinder jacket, the tympan, the cutting and scoring dies, the counterdie, and the material which is being operated upon. The plane of section is on the line 13—13 of Figure 1.

40 In its preferred form our invention is applied to a press which is in general similar to a two-color flat-bed press, comprising a frame 6 having ways 7 upon which the table 8 for holding the type and the cutting and scoring dies is slidably mounted. Standards 9 and 11 project above the frame, and carry slidably mounted journal blocks 12 which are pressed upwardly by springs 13.

45 Journalized in the bearing blocks 12 are the impression cylinders 14 and 16. Between the impression cylinders is journaled a transfer cylinder 17, which is half the diameter of the impression cylinder 14 and is geared thereto for rotation in the opposite direction and at the same peripheral speed. A suitable prime mover, not shown, drives the impression cylinders through appropriate gearing. The same prime mover reciprocates the table 8 by means of a spool gear 18 (see Figure 12)

50 which is splined to a shaft 19 on which it is reciprocated by the cam 21 and lever 22 so as to engage alternately with racks 23 and 24. When the spool gear engages rack 23 the table is driven forward, or to the right. When

55 the rack 24 is engaged the table is driven to

the left. The gear train is so designed that the table travels at the same speed as the periphery of the impression cylinder 14.

70 A certain amount of backlash exists in the gear train, which would militate against exact registry were it not taken up. This is accomplished by the registry racks 31, 31' on the table, which engage the segments 32, 32' on the cylinders at the start of the impression. The rack 31' and gear segment 32' are slightly longer than 31 and 32, and engage an instant before the impression occurs, disengaging after the impression is well started. This accelerated engagement serves to steady the motion of cylinder 16, and damp out vibration which otherwise would be transmitted back to the printing cylinder. This seemingly minor change from ordinary practice has been found to be of major effect in improving 75 the quality of printing done by the press.

80 In order to relieve the shock which the sudden change in direction of the table would otherwise produce, a dash pot 33 is provided at each end of the press, into which works a piston 34.

85 As has been stated, the bearing blocks 12 in which the cylinders 14 and 16 are journaled, are forced upward by the springs 13, which hold the impression cylinders out of contact with the press bed upon the recovery stroke of the table, i. e., when the periphery of the cylinders is moving in the opposite direction from the press bed. Upon the forward or working stroke of the bed the cylinders are forced down against the action of the springs 13 by means of cams 36 which are actuated by cranks 37, connecting rods 38, and bell cranks 39. Each of the bell cranks has a cam follower 41 which travels in a camway 42 found in a cam gear 43. The action of the cams on the two cylinders is similar, but the cams are preferably so formed that the drop or movement to and from the press bed of the cylinder 16 is greater than that of the cylinder 14.

90 Both of the impression cylinders are provided with grippers 46 which are positioned in horizontal grooves 47 formed in the cylinders. The grippers on each cylinder are mounted on a rocker shaft 49, the end of which carries a cam 51. They are actuated by this cam striking pins 53 and 54 which are slidably mounted in the frame of the machine, and actuated by a rocker arm 56 as is best shown in Figure 7. When the pin 53 projects the upper end of the cam 51 strikes it, releasing the gripper.

95 The gripper is held alternately in the open and closed position by means of the spring 57 which works against the arm 58 and forms a compression toggle. The gripper is closed by the other end of the cam 51 striking against the pin 54 which is projected by the rocker arm to accomplish this action. The grippers hold the material 59 against blocks 100

61 which have corrugated surfaces against which the material is held and which are mounted adjustably on the bell crank 62, permitting them to be positioned accurately.

5 Each of the impression cylinders makes one revolution, and the transfer cylinder makes two revolutions, for each of the forward and return strokes of the table 8. The timing of the device can best be shown by the dia-
10 grammatic Figures 2 through 6. The material is fed from the table 66, the grippers on cylinder 14 closing to receive it and carrying it around the cylinder, which drops to impress it against the type on the forwardly moving
15 table as shown in Figure 2.

The drop of cylinder 14 occurs approximately one-half revolution after the gripper has closed, the cylinder remaining down for another half revolution. After still another 20 quarter revolution, or one and one-fourth revolutions after the grippers have closed, the leading edge of the sheet is in position to be transferred to the transfer cylinder 17, whose grippers close as the grippers on the 25 impression cylinder 14 open. The material is carried around the transfer cylinder as is shown in Figure 3, the direction of its curvature being reversed, and the printed side of the sheet being held away from actual contact with the surface of the transfer cylinder by the toothed rings 67 which are spaced at 30 intervals along the transfer cylinder as is best shown in Figure 10. The transfer cylinder carries the sheet of material for one and one-quarter revolutions, its grippers opening simultaneously with the closing of the grippers on the impression cylinder 16. As the grippers on the cylinder 16 close upon the first sheet, the grippers on the cylinder 40 14 close upon a second sheet of material which follows through the same cycle as the first.

During the time when the sheet is on the transfer cylinder and the initial period when it is on the impression cylinder 16 both of 45 the cylinders are raised above the press bed which is moving on the recovery stroke. When the sheets have reached the position shown in Figure 4 the bed has reversed its direction the cylinder 14 drops to the im-
50 pression position, the cylinder 16 following it a quarter of a revolution later. The cylinder 16 also carries the sheet for one and one-quarter revolutions, when the grippers are released and the sheet travels to the de-
55 livery 68.

The action as thus far described is similar to that of the ordinary two-color press, except for the fact that the motion of the cylinder 16 is greater than that of the cylinder 14 in order to clear the cutting and scoring die, which is secured to the press in a chase 69 in the same manner as would be the case with type. The cutting and scoring die is made up of cutting rules 71 and scoring rule 72 held in place by wooden blocks 73.

In order to facilitate the cutting and scoring action, however, the cylinder 16 differs materially from the impression cylinder 14. The cylinder itself is of slightly smaller diameter than the cylinder 14, and circling slightly more than half the cylinder is a removable jacket 76, along the straight edges of which are secured locking wedges 77. The outer edges of these wedges, which are coincident with the edge of the jacket, are substantially radial. The inner edges are slanted to engage wedges secured to the cylinder itself. Of these latter wedges the wedge 78, mounted immediately behind the grippers at the edge of the groove 47 is fixed, and carries a bar 79 which supports the edge of the jacket against the impact of the cutting die.

The wedge 81 at the trailing edge of the jacket is movable by means of the screws 82 to engage the wedge 77 and pull the jacket tightly against the periphery of the cylinder, as is shown in Figure 9.

Since the transfer cylinder makes two revolutions for each revolution of the impression cylinder 16, and since the jacket extends over slightly more than half of the periphery of the impression cylinder, provision must be made to allow the grippers on the transfer cylinder to clear the trailing edge of the jacket. This is accomplished by forming openings 83 in the trailing edge which are spaced to register with the transfer cylinder grippers. The extension of the jacket beyond the half circumference permits it to be solidly supported by the cylinder itself over its entire working surface, so that there is no need to provide support for the wedge 77 on the trailing edge.

In operation a counterdie 84 is built up on the jacket as is shown in Figure 13, this counterdie worked to form grooves or matrices which cooperate with the scoring rulers 72 and knives 71 of the die. It is evident that this requires a separate counterdie for each die that is used.

A tympan 85 is usually built up under the jacket in order to secure perfectly even cutting and scoring. As previously stated, the cylinder 16 is of slightly smaller diameter than the cylinder 14. This difference in size however is made up by the thicknesses added by the tympan, jacket and counterdie, so that in operation the two impression cylinders are of substantially equal diameter to coordinate in their action relative to the table and transfer cylinder.

In the ordinary type of color press the delivery which receives the material from the cylinder 16 is mounted upon the standard 11, and so covers the surface of the cylinder as to make the removal of the jacket impossible without dismantling the press. In the device of our invention the entire delivery is mounted upon a bracket 86 which

is completely separated from the standard 11. The delivery comprises a pivotally mounted arm 87 which carries pulleys 88 on which run the usual delivery belts 89 and also carries projecting fingers 91. A lever 92 is fixed to the arm 87 and is operated by means of a link 93, lever 94 and cam 96 so that the fingers are dropped in place against the cylinder at the proper moment, 10 and the material is shot forward between the delivery belts. When it is desirable to change the jackets upon the cylinders the link 93 may be uncoupled from the lever 92 and the delivery raised out of the way, leaving the cylinder 16 unobstructed.

By means of our invention work of the highest quality can be produced economically. The press is largely interchangeable with well developed apparatus, facilitating 20 servicing and repair; make ready is simple and convenient; and any desired set-up may be preserved for future use.

We claim:

1. In a press, the combination with a type 25 carrying bed and a cylinder for impressing the material to be printed against the type, of a rule die secured to said bed, a second cylinder for impressing the material against said die, means on each of said cylinders for holding a sheet of material and means for transferring the material from said first cylinder to said second cylinder.

2. In a press, the combination with a type 35 carrying bed and a cylinder for impressing the material to be printed against the type, of a second cylinder for impressing the material against a rule die, a jacket removably secured to said second cylinder, means on each of said cylinders for holding a sheet of material and means for transferring the material from said first cylinder to said second cylinder.

3. In a press, the combination with a type 45 carrying bed and a cylinder for impressing the material to be printed against the type, of a rule die secured to said bed, a second cylinder for impressing the material against said die, a transfer cylinder, grippers on said transfer cylinder, and a removable jacket enclosing 50 a portion of said second cylinder and having openings in the trailing edge thereof for clearing the grippers on said transfer cylinder.

4. In a press having a reciprocating type 55 carrying bed, a printing impression cylinder, a cutting impression cylinder, means for transferring the material to be printed from the printing to the cutting cylinder, means for moving said printing cylinder to and from the bed on the printing and cutting strokes respectively, and means for moving the cutting cylinder through a greater distance to and from the bed on said strokes.

5. In a press having a reciprocating type 65 carrying bed, a printing impression cylinder,

a cutting impression cylinder having a smaller diameter than said printing cylinder, a removable jacket secured to said cutting cylinder, means for transferring the material to be printed from the printing to the cutting cylinder, means for moving said printing cylinder to and from the bed on the printing and recovery strokes respectively, and means for moving the cutting cylinder through a greater distance to and from the bed on said strokes.

6. In a press for printing, cutting, and scoring material and having a reciprocating bed, a printing cylinder, a transfer cylinder, a cutting and scoring cylinder, means on each of said cylinders for gripping the material, a removable jacket secured to the cutting and scoring cylinder, and a delivery coordinated with said cutting and scoring cylinder and mounted separately therefrom for receiving material from the cutting and scoring cylinder and movable to permit access to said cylinder for removing the jacket.

7. In a press having a reciprocating type 90 carrying bed, a printing impression cylinder, a cutting impression cylinder, a rack and gear segment on said bed and printing cylinder timed to engage at the instant of impression of said printing cylinder, and a longer rack and segment on said bed and cutting cylinder timed to engage prior to the instant of impression of said cutting cylinder.

In testimony whereof, we have hereunto set our hands.

GEORGE F. FORD. 100
WALTER PITTMAN.
